UNITED STATES PATENT OFFICE.

ALBERT PATITZ, OF MERIDEN, CONNECTICUT, ASSIGNOR TO THE BRADLEY & HUBBARD MANUFACTURING COMPANY, OF SAME PLACE.

DESIGN FOR A HOLDER FOR LAMP-FOUNTS.

SPECIFICATION forming part of Design No. 24,128, dated March 19, 1895.

Application filed February 18, 1895. Serial No. 538,904. Term of patent 3½ years.

To all whom it may concern:

Be it known that I, ALBERT PATITZ, of Meriden, in the county of New Haven and State of Connecticut, have invented a new Design for a Lamp-Fount Holder, (Case A;) and I do hereby declare the following, when taken in connection with the accompanying drawings and the letters of reference marked thereon, to be a full, clear, and exact description of the same, and which said drawings constitute part of this specification, and represent, in—

Figure 1, a side view of a lamp-fount holder embodying my design; Fig. 2, an under side view thereof.

This invention relates to a design for a lamp-fount holder, and the design consists in the configuration and ornamentation of the fount-holder as shown in the accompanying illustrations.

The fount-holder is bowl-shaped in general outline, its lower portion A formed by a series of oak-leaves B, springing from the center and curving upward and outward, forming the

bottom of the holder. Above these oak-leaves B is a rib C, from which springs a series of plain oval medallions D, surrounded by narrow scrolls, these medallions alternating with upwardly springing foliated sprays E. Above these medallions and sprays is a rib F, and above this rib is a slightly concaved band G of open scroll-work, having at its upper edge a plain rib H, forming the upper configuration of the fount-holder, all as shown in the accompanying illustrations.

I claim—

The design for a lamp-fount holder as herein described and shown in the accompanying illustrations.

In testimony whereof I have signed this specification in the presence of two subscribing witnesses.

ALBERT PATITZ.
